UNITED STATES PATENT OFFICE.

SAMUEL WARD FRANCIS, OF NEW YORK, N. Y.

MACHINE FOR CANCELING POSTAGE AND OTHER STAMPS.

Specification forming part of Letters Patent No. 38,222, dated April 21, 1863.

To all whom it may concern:

Be it known that I, SAMUEL WARD FRANCIS, of New York, in the county and State of New York, have invented certain new and useful Improvements in Adhesive-Stamp Canceling Instruments; and I hereby declare that the following, taken in connection with the accompanying drawings, forms a full, clear, and exact description of the same.

The object of my invention is to prevent postage or other adhesive stamps from being used more than once, by permanently defacing them. The canceling of stamps by writing or printing ink—*i. e.*, by writing or printing over them the canceling mark—has proved inefficient. Stamps so canceled may be readily removed from the envelope or paper to which they are attached, and the canceling mark obliterated by means of chemical reagents; and my invention consists, first, in the method of canceling adhesive stamps by means of a cutting-edge or series of cutting-edges, so operated that when applied to the stamps one or more portions thereof shall be cut out and removed without injury to the material to which the stamps are attached; second, in the combination and construction of a hand instrument for canceling stamps by cutting, as before referred to, so that by one downward pressure its cutters or scrapers shall be operated and remove a portion of the stamp without injury to the paper underneath; third, in the combination, with cutters operated by a sliding handle, of a studded guard and support, so arranged that the instrument is thereby caused firmly to grasp or to impinge upon the surface of the stamp to be canceled while the cutters are being operated, and to guard the cutters against undue pressure upon the paper; fourth, in the combination, with the cutters of a hand instrument for canceling stamps by cutting out of and removing from the stamp one or more portions thereof, of a spring so arranged as to bear the cutter upon the stamp with a pressure requisite to produce an incision in the paper of a depth not exceeding the thickness of stamps.

In the accompanying drawings, Figures 1 and 2 represent an elevation and a longitudinal section of an instrument embodying the principle of my invention; Fig. 3, a bottom view of the same; and Fig. 4 a sectional elevation of another instrument constructed in accordance

with my said invention, being merely a modification of the former.

The instrument shown in Figs. 1, 2, and 3 of the accompanying drawings is composed of a handle and of a rotary cutting device. The handle M forms the sleeve to a spiral spring, K, butting against the head T of the shank F, and against a cap-piece, L, so shaped as to freely turn upon its own axis, (which is also the axis of the sleeve and the spring,) when in the operation of the instrument the tendency produced on the spring is to rotate it, and thus prevent friction and strain upon the spring. The sleeve is closed at its underside by means of a plug, G, through the central orifice of which the shank F passes, and is capable of a reciprocating up-and-down play. The plug G is provided with a pin, H, protruding from the interior face of its orifice and fitting a helical groove, cut into the surface of the shank. By this arrangement the shank is rotated within the sleeve, the latter is caused to slide on the shank, and thus impart to it a reciprocating up-and-down motion.

Instead of a pin in the sleeve and helical groove on the shank, a twisted or helical shank may be used, of an angular, oblong, or other suitable sectional area in connection with a nut in the end of the sleeve or handle fitting the shank, so that the shank when forced up or down through the nut will thereby be rotated.

To the enlargement F' of the lower extremity of the shank is riveted the cylinder or guard E, which contains the cutter R, and a studded spindle, A, around which the cutter revolves. The principal office of the cylinder, however, is to act as a guard to the cutters so as to prevent their being pressed upon or into the paper with a force greater than that due to the elasticity of the spring. The under surface of the enlargement F' as well as the head of the spindle A are convex, so that there will be but little friction when the shank is rotated upon the spindle, rendered fixed or stationary by the pressure upon it of the sleeve. The cutting-edges or cutters are wrought into the end of a steel ring, R, and are of such form and inclination relatively to the paper when applied thereto as to produce a shaving cut. The cutter is held in position by a pin, D, screwed into the cylinder E, and entering a slot in the cylindrical cutter, or vice versa, by a pin which is fitted in the cutters, and has a limited play in

a slot in the cylinder, the object being to allow the cutters to rise within the cylindrical sleeve until flush with its surface underneath. The spindle A is held in position by an intermediate spiral spring, C, resting on top of the cutting cylinder and butting against the flange of the head. This spring C exerts a pressure on the cutters sufficient only to allow it to penetrate paper the usual thickness of a stamp.

The operation of the instrument will be readily understood from the above description of parts and their adjustment. The instrument is seized by the handle, its cutters applied to the stamp to be canceled, and the handle is depressed. As soon as pressure is exerted on the handle the points or studs on the center spindle impinge upon the stamp and prevent and hold the paper immovably to the action of the cutters. Further downward pressure of the handle causes it to slide down along the shank, whereby the latter is rotated, but the rotation of the shank carries with it the cutters, whose edges, actuated by the spring, have slightly indented the paper. The rotation of the cutters therefore chips off the stamp an annular portion thereof, and thus irretrievably spoil it. On releasing the pressure from off the paper the shank is pushed out by the spring, and all the parts resume the original position relatively to each other, as shown in Fig. 2.

Fig. 4 of the accompanying drawings represents a simplified instrument. The cutters in this instance remove a straight strip or strips from the stamp. They are formed on a curved edge of a bell-crank-shaped lever, the short end of which is connected with a piston-rod, A, and thereby operated when depressed, which causes the cutters to vibrate on their suspension-centers. A spring, B, resting on a rim or studs, C, automatically closes the cutters after each operation. Points or studs on the sleeve D perform the same functions as the

center spindle in the instrument previously described.

Having thus fully described my invention, and the manner in which the same is or may be carried into effect, I shall state my claims as follows:

1. The method of canceling adhesive stamps by means of a cutting-edge or series of cutting-edges, so operated that when applied to the stamps one or more portions thereof shall be cut out and removed without injury to the material to which the stamps are attached, substantially as set forth.

2. The combination and construction of a hand instrument for canceling stamps by cutting, as before referred to, so that by one downward pressure its cutters or scrapers shall be operated to remove a portion of the stamp without injury to the paper underneath, substantially as set forth.

3. The combination, with cutters operated by a sliding handle, of a studded guard and support, so arranged that the instrument is thereby caused firmly to grasp or to impinge upon the surface of the stamp to be canceled while the cutters are being operated, also to guard the cutters against undue pressure upon the paper, substantially as set forth.

4. The combination, with the cutters of a hand instrument for canceling stamps by cutting out of and removing from the stamp one or more portions thereof, of a spring so arranged as to bear the cutter upon the stamps with a pressure requisite to produce an incision in the paper of a depth not exceeding the thickness of stamps, substantially as set forth.

In testimony whereof I have signed my name to this specification before two subscribing witnesses February 16, 1863.

SAML. W. FRANCIS.
